UNITED STATES PATENT OFFICE

ROBERT K. WINNING, OF WAUWATOSA, WISCONSIN, ASSIGNOR TO CLUM MANUFACTURING COMPANY, OF MILWAUKEE, WISCONSIN, A CORPORATION OF WISCONSIN

LIGHT-DIMMING SWITCH

Application filed June 12, 1929. Serial No. 370,249.

This invention relates to improvements in light dimming switches of the type patented to me in United States Letters Patent 1,678,686 dated July 31, 1928.

As in the case of the prior patent above referred to it is an object of the present invention to provide a switch which will necessarily function to leave either the bright headlight or the dim headlight circuits closed 10 at all times so that the operator of a vehicle equipped with this device cannot at any time be wholly deprived of light due to any failure of the switch to function properly. The present invention however, has as its further 15 object provision of a construction such that it is impossible for both the bright and dim headlight circuits to be closed simultaneously except momentarily during the operation of the switch. It is desired also to provide for 20 this momentary over-lap whereby one circuit will be closed before the other is opened.

A further object of the invention has to do with simplification and reduction of expense by the elimination and modification of 25 parts. It is my further purpose to provide a balanced means for operating the switch.

In the drawings:

Figure 1 is a vertical section through a switch embodying the present invention in 30 a plane parallel to the axis thereof.

Figure 2 is a rear elevation of the switch with a portion of its terminal head broken away to expose the interior construction.

Figure 3 is a detailed view of the actuating 35 mechanism with the terminal head and the switch rotor removed.

Figure 4 is a detailed view in end elevation of the portion of the switch rotor engaged by the ratchet whereby it is actuated.

Like parts are identified by the same reference character throughout the several views.

The switch casing 5 comprises a hollow shell closed at one side by a terminal head 6 and has spot welded to its upper end mounting plate 7. Riveted to plate 7 is a tubular guide 8 for the plunger 9 which carries the pedal member and spring housing 10. Plunger 9 and pedal 10 are normally supported by a compression spring at 11 which 45 encircles the guide 8.

Within the casing is a reciprocable part 15 formed of sheet metal to provide spaced arms 16 and 17, the latter of which is toothed at 18. The top of plate 15 is bent over at right angles to provide a part 19 to which plunger 9 is riveted. When the plunger is reciprocated the plate 15 functions as a slide moving in face contact with the wall of casing 5.

Projecting centrally from the rear wall of the casing 5 between arms 16 and 17 of the slide 15 is a stud 20 upon which the rotary parts of the device are mounted. Immediately adjacent the rear wall of the casing a driving ratchet member 21 is mounted on the stud and provided with three teeth 22 meshing with the rack teeth 18 of arm 17 of the slide. The other arm 16 of the slide may engage the untoothed peripheral portion of the driving ratchet 21 as shown in Figure 3 70 whereby to take up any thrust developed in the mesh of teeth 18 and 22.

Pressed upwardly from the face of the driving ratchet are ratchet teeth 23, which are preferably three in number. The number should at least be kept reasonably small in order to reduce excessive wear on the driven ratchet member.

In the present embodiment of the invention the driven ratchet member comprises a dielectric rotor 25 mounted on the stud of post 20 and provided in its rear face with integrally formed teeth 26 complementary to the teeth 23 of the driving ratchet. In the particular device illustrated there are six of the driven teeth 26 and neither the driving nor the driven teeth have a great deal of elevation, it being desirable to provide for the transmission of rotative movement with a minimum of axial movement in the particular switch under consideration.

The driven ratchet rotor 25 presents toward the terminal head 6 of the switch an enlarged disc-like face portion 28 in which radial grooves 29 are formed. The present 95 switch has three such grooves. A conductive contact plate 30 is applied to the face of the rotor and includes radially extending wings 31 having fingers 32 clamping the contact plate to the rotor as shown in Fig. 1 and 100

Fig. 4. The wings 31 are spaced apart sufficiently to expose in the dielectric composition of the rotor 25, the grooves 29 above described.

5 The terminal head 6 is provided with three terminals 33, 34 and 35 each of which has, within the case, resilient fingers 36 bearing on the rotor. The finger connected with terminal 34 bears permanently upon the conductive plate 30 applied to the face of the rotor, whereas the fingers connected with terminals 33 and 35 project into engagement with that portion of the rotor face which includes the exposed dielectric material in which grooves 10 15 29 are formed.

The direction of rotation of the switch rotor is such that the last mentioned contact fingers trail over the face of the rotor, being disposed to project in opposite directions at 20 opposite sides of the case of the rotor as shown in Fig. 1. The extremity of each of the spring fingers 36 is inwardly curved toward the face of the rotor whereby each of the trailing fingers connected with terminals 33 and 35 25 functions as a dog or pawl to engage in the grooves 29 in the dielectric body of the rotor to prevent reverse rotation of the rotor during depression of the pedal. The fingers are also projected bodily away from the plane of 30 the terminal head 6 and thereby tend to force all of the rotative parts toward the rear of the casing. The pressure of these spring fingers on the rotative parts provides all of the spring pressure required for the operation of 35 the ratchets with which the switch is provided. At the same time the ratchets are so designed that the movement occasioned in these springs by the ratching operation is very slight and is not sufficient to distort the 40 springs.

The device is so organized that when the pedal 10 is depressed the rack teeth 18 will coact with segment teeth 22 to oscillate the driving ratchet member 21 in a counter-clockwise direction as viewed in Fig. 3. In this direction of rotative movement the driving ratchet teeth 23 will ratchet over the complementary opposed teeth 26 of the driven switch rotor 25, the rotor moving axially 45 50 against the pressure of contact springs 36 to permit of this ratcheting operating.

When the pedal 10 is fully depressed and has been released it will be impelled upwardly by compression spring 11 thereby producing clockwise rotation of the driving ratchet as 55 viewed in Fig. 3. The teeth 23 are now moving in a direction for engagement with teeth 26 of the switch rotor and accordingly the switch rotor is caused to rotate with the driving ratchet member 21. In the course of such 60 rotation the contact springs 36 with terminals 33 and 35 will trail over the face of the rotor. One of them will initially have been engaged in one of the grooves 29 and the 65 movement of the rotor will bring beneath

this contact spring one of the conductive wings 31 of the moving contact plate 30. The other will initially have been engaged with one of the wings 31 and the movement of the rotor will bring beneath this contact spring a dielectric portion of the rotor having a groove 29 which, in the ultimate position of the parts, will register with the end of the spring.

The engagement of the inwardly curved extremities of the contact fingers with the grooves 29 will hold the rotor against reverse movement when the pedal is again depressed.

It will be observed that the arcuate extent of the wings 31 of the movable contact plate is such that during the movement of the switch from one position to another the two contact springs connected respectively with terminals 33 and 35 will momentarily both engage the moving contact switch. This ensures the closing of one circuit before another is opened and when the switch is employed as a dimming switch for motor vehicle purposes it makes it impossible for the operator of the motor vehicle to be deprived of light by any operation of this switch. It is equally impossible, however, for the switch to remain in a position such that both circuits will be closed, since the functioning of the switch after the foot pedal has been depressed and released is purely automatic and the extent of operation is necessarily predetermined by the organization of the parts so that each movement of the contactor will bring one of the exposed dielectric portions thereof beneath one of the circuit terminals 33 or 35. Unless the pedal has been depressed to the full extent required for this movement of the parts the driving and driven ratchet teeth will not engage for the rotation of the rotor. Hence it is assured that the switch will come to rest in the desired position.

I claim:

1. In a switch, the combination with fixed contacts, and a pivotally movable contact means arranged for co-action therewith, of mechanism for moving said contact means comprising a reciprocable plate provided with spaced arms, rack teeth formed marginally in one of said arms, and a contact actuator comprising a disc pivoted between said arms in the plane of said plate and provided with peripheral teeth meshing with said marginal rack teeth.

2. In a switch, the combination with fixed contacts, and a pivotally movable contact means arranged for co-action therewith, of mechanism for moving said contact means comprising a reciprocable plate provided with spaced arms, rack teeth formed marginally in one of said arms, and a contact actuator comprising a disc pivoted between said arms in the plane of said plate and provided with peripheral teeth meshing with said marginal

rack teeth, the untoothed arm of said plate being in peripheral engagement with an untoothed peripheral portion of said actuator.

3. In a switch, the combination with a movable contact carrier provided with ratchet teeth, and an oscillatable contact actuator provided with complementary ratchet teeth, of a terminal head, means limiting the movement of the contact actuator therefrom, and 10 complementary contacts carried by the contact carrier and the terminal head, certain of which are resiliently adapted to exert pressure in a direction tending to separate the contact carrier and terminal head and constituting the sole means for maintaining said ratchet teeth in operative engagement.

4. In a switch, the combination with a terminal head and a contact carrier rotatable with respect thereto, of a complementary contact means on said head and carrier, one of said contact means being resiliently subject to compression and adapted to force said carrier and head apart, and a device opposing separation of said contact carrier and head 25 comprising a contact actuator secured against axial separation from said head and positioned co-axially with said carrier, means for oscillating said actuator, and complementary ratchet teeth disposed on said carrier and 30 actuator for inter-engagement in one relative direction of oscillation thereof, said resilient contact means being adapted to maintain said teeth in effective engagement while permitting sufficient yielding of said carrier for 35 slippage between said teeth in one direction of rotative oscillation between the actuator and the carrier.

5. In a switch, the combination with a terminal head and a rotatable contact carrier, of 40 a contact actuator co-axial with said carrier and secured against axial separation from said head, co-acting ratchet teeth upon said actuator and carrier, a contactor and a dielectric stop upon said carrier, and a resilient contact upon said terminal head engageable alternatively with said stop and with said contactor, and adapted in engagement with said stop to secure said carrier against rotation in a direction opposed to that in which 45 said carrier is rotated by said ratchet teeth.

6. In a switch, the combination with a terminal head and a rotatable contact carrier, of 55 a contact actuator co-axial with said carrier and secured against axial separation from said head, co-acting ratchet teeth upon said actuator and carrier, a contactor and a dielectric stop upon said carrier, and a resilient contact upon said terminal head engageable alternatively with said stop and with said 60 contactor, and adapted in engagement with said stop to secure said carrier against rotation in a direction opposed to that in which said carrier is rotated by said ratchet teeth, 65 said resilient contact being adapted to pro-

vide pressure for maintaining said ratchet teeth in operative engagement.

7. In a switch, the combination with a terminal head member and a rotatable contact carrier member associated therewith, of dielectric teeth presented by one of said members toward the other, contacts intervening between said teeth on the member provided with such teeth, resiliently yieldable contacts carried by the other of said member and 70 formed to constitute pawls for co-action with said teeth as well as for electrical engagement with the intervening contact, and a ratchet mechanism for actuating said carrier member in a direction such as to free a resilient contact from a detent tooth engaged therewith, 75 said ratchet mechanism including complementary ratchet teeth held in engagement by the thrust of said contacts.

8. In a switch, the combination with a terminal head provided with spring contact pawls, of a dielectric contact carrier mounted for rotation and provided with exposed dielectric teeth for inter-action with said pawls to secure said carrier from rotation in one direction while permitting rotation in the opposite direction with respect to said head, contacts on said carrier between said teeth, ratchet teeth on said carrier, an actuating ratchet provided with complementary teeth, 85 and means for oscillating said actuating ratchet, a contact on said terminal head being resiliently engaged with said carrier in a direction to maintain its ratchet teeth in engagement with the teeth of said actuating ratchet.

9. In a switch, the combination with a terminal head provided with a plurality of terminals, a contact carrier rotatable with respect to said head, a spring contact arranged to provide permanent electrical connection between a portion of said carrier and one of said terminals, said contact acting resiliently on said carrier in an axial direction tending to thrust it from said head, contact means on 100 said carrier electrically connected to said spring contact, additional contacts providing for the making and breaking of electrical connections between the contact means of said carrier and remaining terminals of said head, 105 and ratchet means for rotating said carrier including complementary teeth separable in the direction of the carrier axis and maintained in engagement by the pressure of said first mentioned contact.

10. In a switch adapted alternatively to establish different circuits closing one and only one except during transition from the closing of one circuit to the closing of the other, the combination with a pair of contact carriers one of which is relatively fixed and the other relatively movable, of a supply terminal, a plurality of take-off terminals connected with the fixed carrier, complementary contacts for said carriers having relative 115 120 125 130

arcuate extent such as to provide a momentary over-lapping of engagement between the live terminal and the two take-off terminals of said head, the disposition of said contacts being such that in predetermined consecutive positions of the movable contact carrier circuits will be closed alternatively to different take-off terminals, and means for the advance of the movable contact carrier in predetermined steps adapted in each instance to leave said contact carrier in one of said positions.

11. In a device of the character described, the combination with a terminal head and a rotatable contact carrier, of a contact plate applied to the face of said carrier provided with radial contact wings exposing dielectric portions of said carrier therebetween, a contact connected with said head and permanently engaged with said plate, and an additional contact spring connected with said head and disposed in the path of movement of said wings whereby alternatively to contact with said wings and with dielectric portions of said carrier.

12. In a device of the character described, the combination with a terminal head and a rotatable contact carrier, of a contact plate applied to the face of said carrier provided with radial contact wings exposing dielectric portions of said carrier therebetween, a contact connected with said head and permanently engaged with said plate, and an additional contact spring connected with said head and disposed in the path of movement of said wings whereby alternatively to contact with said wings and with dielectric portions of said carrier, said carrier being provided with detent teeth and said spring contact being formed to constitute a resiliently yieldable dog co-acting with said teeth to restrain said carrier against movement in one direction and permit it to move freely in the opposite direction of rotation.

13. In a device of the character described, the combination with a terminal head and a contact carrier rotatable with respect thereto, of a contact plate applied to the face of said carrier and provided with three radially extending wings exposing intervening dielectric portions of said carrier, spring contacts carried by said terminal head and engageable with said plate, one of said contacts being positioned to ride alternatively from said wings to dielectric portions of said carrier in the rotation of the latter.

14. In a device of the character described, the combination with a terminal head and a contact carrier rotatable with respect thereto, of a contact plate applied to the face of said carrier and provided with three radially extending wings exposing intervening dielectric portions of said carrier, spring contacts carried by said terminal head and engageable with said plates, one of said contacts being positioned to ride alternatively

from said wings to dielectric portions of said carrier in the rotation of the latter, and another contact spring carried by said terminal head being adapted simultaneously to ride from a dielectric portion of the carrier onto one of said wings during such rotation. 70

15. In a device of the character described, the combination with a terminal head and a contact carrier rotatable with respect thereto, of a contact plate applied to the face of said carrier and provided with three radially extending wings exposing intervening dielectric portions of said carrier, spring contacts carried by said terminal head and engageable with said plates, one of said contacts being positioned to ride alternatively from said wings to dielectric portions of said carrier in the rotation of the latter, and another contact spring carried by said terminal head being adapted simultaneously to ride from a dielectric portion of the carrier onto one of said wings during such rotation, said wings having an arcuate extent such as to ensure the engagement of one of said contacts with a given wing before the other of said contacts becomes disengaged from its wing of said plate. 80

16. In a device of the character described, the combination with a terminal head and a contact carrier rotatable with respect thereto, of a contact plate applied to the face of said carrier and provided with three radially extending wings exposing intervening dielectric portions of said carrier, spring contacts carried by said terminal head and engageable with said plates, one of said contacts being positioned to ride alternatively from said wings to dielectric portions of said carrier in the rotation of the latter, and another contact spring carried by said terminal head being adapted simultaneously to ride from a dielectric portion of the carrier onto one of said wings during such rotation, said wings having an arcuate extent such as to ensure the engagement of one of said contacts with a given wing before the other of said contacts becomes disengaged from its wing of said plate. 90

17. In a device of the character described, the combination with a terminal head and a contact carrier rotatable with respect thereto, of a contact plate applied to the face of said carrier and provided with three radially extending wings exposing intervening dielectric portions of said carrier, spring contacts carried by said terminal head and engageable with said plates, one of said contacts being positioned to ride alternatively from said wings to dielectric portions of said carrier in the rotation of the latter, such steps being so determined with reference to the arcuate extent of said wings as to ensure against the engagement of more than one of said contacts with a wing of said plate at any time said carrier is at rest. 100

ROBERT K. WINNING. 110
